FOLDER

Cyril I. Harby, Rochester, N. Y., assignor to Yawman & Erbe Mfg. Co., Rochester, N. Y., a corporation of New York

Application June 10, 1932, Serial No. 616,422

13 Claims.

(Cl. 93—1)

This invention relates to folders and more particularly to reinforced folders, and the method of making the same.

In the past it has been the practice to reinforce one margin of certain types of correspondence folder, by attaching to said margin a reinforcing strip of material. According to the usual practice, this reinforcing strip has been formed by folding over some of the material of the folder and adhesively fastening it to the body of the folder. Much difficulty has been encountered in the making of prior folders in applying the adhesive so that after the finishing operation, it will extend exactly to the free edge of the strip since it has been found that either the adhesive is extruded beyond the edge of the reinforcing strip where it presents an unsightly appearance, or else the adhesive fails to reach the edge of the strip in which case the edge becomes loose, so that it will catch the correspondence sheets and subsequently will become mutilated.

In accordance with the present invention a novel method is provided for manufacturing or finishing a folder having a reinforcing marginal strip wherein the edge of the strip is securely fastened adhesively to the body of the folder.

An additional feature of the invention relates to the method of finishing a reinforced folder wherein in certain areas of the edge of its reinforcing marginal strip is partially embedded into the material of the body of the folder, thereby providing a secure adhesive bond between the edge of the strip and the material of the body.

A further feature of the invention relates to the method of finishing a folder having a reinforcing marginal strip which comprises reinforcing the free edge of the marginal strip so that in the event that the adhesive bond between the edge of the strip and the body of the folder becomes loose, the reinforced edge will still be held in close relation to said body.

Another feature of the invention relates to a novel folder having a reinforcing marginal strip wherein the edge of the strip at spaced intervals is depressed into the body of the folder.

For a clearer understanding of the invention, reference is made to the drawing in which Fig. 1 is a perspective view of a folder having a reinforced marginal strip according to the present invention; Fig. 2 is an enlarged sectional view taken substantially on the line 2—2 of Fig. 1, indicating the construction of the tab portion of the reinforced margin of the folder; Fig. 3 is a fragmentary view of an enlarged portion of the folder showing the reinforcing corrugations along

the free edge of the marginal strip at the reinforced portion of the folder; Fig. 4 is a sectional view taken on the line 4—4 of Fig. 3; Fig. 5 is a diagram showing certain of the more important steps of manufacturing a folder; Figs. 6, 7, 8 and 9 represent fragments of modified forms of the invention wherein various shapes or patterns of reinforcing depressions are provided along one edge of the reinforcing marginal strip.

Referring especially to Fig. 1, 5 generally designates a folder formed of manila stock and having the parts or body portions 6 and 7 hingedly connected together along a line of scoring 8. The upper edge of the portion 7 is formed with a reinforcing marginal strip 9 which terminates near one end in a tab 10. This tab 10 besides providing a surface for a label 11, also serves as means to be grasped in removing the folder from a cabinet in which it is stored. The reinforced margin may be formed by a separate strip applied to the portion 7, but it is preferred to form it integral with this portion at the tab 10, as shown in Fig. 2. The reinforcing marginal strip 9 is adhesively fastened to the body portion 7, but in the past much difficulty has been encountered in manufacturing such reinforced folders since either the adhesive failed to reach the edge 12 of the marginal strip when pressure was applied thereto during the finishing operation, or else the adhesive was extruded beyond the edge 12 so that it presented an unsightly appearance. In accordance with the present invention, the portion of the reinforcing strip 9 near its free edge 12 is crimped or corrugated along the parallel lines, such as 13, so that parallel areas of the strip 9 are forced into or embedded into one surface of the body portion 7 of the folder. In this way, the area of the edge of the reinforcing marginal strip is increased and the layer of adhesive between the reinforcing strip 9 and the body portion 7 is forced into the fibers of the material of each of these parts, thereby forming a very strong adhesive bond between them. It should be noted that the lines or corrugations 13 are formed by applying concentrated pressure to these areas which serves to distribute the adhesive uniformly over the desired surfaces, and in addition brings the parts 9 and 7 into more intimate contact.

Although the reinforced folder may be made according to any one of several methods, the 50 method diagrammatically indicated in Fig. 5 has been found to be especially satisfactory. In this method a rectangular sheet of stock of proper size and scored along the lines 8, 15 and 16, has an adhesive, such as glue applied to the area 55

thereof designated 17. It will be noted that this adhesive area does not extend to the edge 12 of the folder, but is preferably spaced therefrom at a distance of not more than $\frac{1}{2}$ of an inch. This unglued narrow strip adjacent the edge 12 of the folder is intended to be indicated by the space between this edge and the fine parallel line adjacent thereto. After the glue is thus applied, the upper edge of the blank 10 is folded along the line of scoring 16 with the reinforcing marginal strip brought into intimate contact with the body 7 of the folder. This folding operation is preferably effected by passing the strip 9 and the upper portion of the blank between pressure rolls (not shown). After this operation and while the glue or adhesive on the area 17 is still moist, the folded edge of the reinforcing strip 9 is crimped against the body 7 such as by passing these portions of the blank between a smooth roll 18 and a crimping roll 19, which crimping roll has its surface embossed to form a series of corrugations, such as 13, (Figs. 3 and 4), in the marginal strip 9, but without depressing or roughening the lower surface of the folder body 7. When the marginal strip 9 has thus been crimped, the blank is passed through a tabbing shear to cut out a portion of the marginal strip 9, leaving the integral tab 10. The final stage of the method comprises folding the blank along the line of scoring 8.

While the preferred form of crimping for the edge of the marginal strip 9, is shown in Figs. 1 to 5, inclusive, wherein the crimping comprises a series of parallel lines at right angles to the edge 12 of this strip, other crimping patterns may be used. In Fig. 6, the crimping is in the form of a series of parallel lines 20 at an oblique angle to the edge 12 of the reinforcing margin. In Fig. 7 the crimping takes the form of a series of X's 21; while in Fig. 8 it assumes the form of a series of lines 22 parallel to the edge 12 of the strip; and in Fig. 9 the crimping is in the form of a series of circles 23. These different crimping patterns may be formed by properly embossing the surface of a crimping roll of the type 19 indicated in Fig. 5.

While in this disclosure several different forms of possible crimping patterns for the edge of the reinforcing strip of a folder are shown, these patterns are shown merely by way of example since the possible number thereof is almost limitless.

What I claim is:

- 55 1. The method of making a folder having a reinforced edge which comprises applying adhesive to one margin of the folder, folding the margin having adhesive thereon into intimate engagement with the body of the folder and embedding spaced portions of the edge of the margin into the material of said body.
- 60 2. The method of making a folder having a reinforced edge which comprises applying adhesive to one margin of the folder, folding the margin having adhesive thereon into intimate engagement with the body of the folder, and increasing the adhesive area of a portion of said margin by crimping the material near the edge thereof while said adhesive is still damp.
- 65 3. The method of making a folder having a reinforced edge which comprises applying adhesive to one margin of the folder, folding the margin having adhesive thereon into intimate engagement with the body of the folder, and
- 70 75

reinforcing the material of said margin adjacent one edge thereof.

4. The method of making a folder having a reinforced edge which comprises applying adhesive to one margin of the folder, folding the margin having adhesive thereon into intimate engagement with the body of the folder, and spreading the adhesive after the step of folding by applying concentrated pressure at spaced areas along one edge of said margin. 10

5. The method of making a folder having a reinforced edge which comprises applying adhesive almost to the edge of one margin of the folder, folding the margin into adhesive engagement with the body of the folder, and applying concentrated pressure at adjacent points along one boundary of said margin in order to spread said adhesive to substantially the free edge of said margin. 15

6. The method of finishing a folder having a free margin reinforced by a strip adhesively fastened to one surface of said margin which comprises crimping an area near one edge of the strip into said margin while the adhesive is still damp, without distorting the other surface of said margin. 20 25

7. The method of finishing a folder including a sheet member having at least one free edge reinforced by a marginal strip member which comprises applying adhesive to a portion of one of said members, and forcing the adhesive while still damp into the material of one surface of said sheet member and said marginal strip member by concentrated pressure applied to areas thereof corresponding to a series of closely related parallel lines without distorting the other surface of said sheet member. 30 35

8. A folder of the class described comprising a sheet of relatively stiff material having two portions joined together by a folding connection, and a reinforcing marginal strip adhesively fastened to one margin of the sheet opposite said connection, the material near one edge of the marginal strip being crimped. 40

9. A folder of the class described comprising a sheet of relatively stiff material having two portions joined together by a folding connection, and a reinforcing strip adhesively fastened to a margin of the sheet opposite said connection, spaced areas of the material near one edge of said strip being partially imbedded in the material at said margin of the sheet. 50 55

10. A folder of the class described comprising two body portions hingedly connected together and having free edges, and a reinforcing strip adhesively fastened to a margin of one of the body portions, the material near one edge of said strip being reinforced by corrugations therein. 60

11. The method of making a folder having a reinforced free edge, said folder being formed from a sheet of relatively heavy paper or cardboard material, which comprises folding the sheet intermediate two of its edges, applying adhesive to a region on one surface of said sheet, folding the margin of the sheet into intimate engagement with the body of the sheet with the adhesive therebetween, and embedding spaced portions of the edge of the margin into the material of said body in the region of the adhesive. 65 70

12. A folder of the class described comprising a body portion of stiff material such as manila stock folded intermediate of two of its edges, and a reinforcing marginal strip also of relatively stiff stock adhesively fastened to the body portion, spaced areas of the material near one edge of the 75

marginal strip being partially imbedded in the material of the body portion, said areas collectively defining a series of parallel lines.

13. A folder comprising a sheet of relatively stiff paper stock having a fold line therein dividing the sheet into two portions, and a flat strip provided with a tab through which said strip is

integrally connected with said sheet, one surface of said strip being fastened by adhesive to said sheet at a margin thereof which is parallel to said fold, spaced areas of said strip near an exposed edge thereof being partially imbedded in said sheet at the region of said adhesive. 5
